UNITED STATES PATENT OFFICE.

CARL A. MOBERG, OF CHICAGO, ILLINOIS, ASSIGNOR TO NORTHAM BROTHERS CO., INC., OF CHICAGO, ILLINOIS, A CORPORATION OF ILLINOIS.

SCROLL SAW.

Application filed December 5, 1931. Serial No. 518,953.

To all whom it may concern:

Be it known that I, CARL A. MOBERG, a citizen of the United States, residing at 2932 North Sawyer Avenue, Chicago, in the county of Cook and State of Illinois, have invented new and useful Improvements in Scroll Saws, of which the following is a specification.

This invention relates to improvements in scroll saws, and will be fully understood by reference to the following specification and accompanying drawings, in which Figure 1 is a view in side elevation of a device embodying the features of my invention, Fig. 2 is a view in side elevation of the cross-head forming a part of the device, Fig. 3 is a view of the device in front elevation, Fig. 4 is a view taken as indicated by the line 4 of Fig. 1, and Fig. 5 is a view taken as indicated by the line 5 of Fig. 3.

As shown in the drawings, 10 indicates a suitable support such as a table top or board, upon which the scroll saw is mounted. 11 indicates a cast base-plate, suitably fastened to the supporting surface 10, as by bolts 12. The base-plate 11 is provided with two upwardly projecting sockets 13 adapted to receive the lower ends of the round posts or rods 14. The rods 14 are held in the sockets 13 by means of set-screws 15. Mounted on the upper ends of the posts 14 is a flat circular work-supporting table 17. The underside of the table 17 is provided with two downwardly projecting sockets 18, adapted to receive the upper ends of the posts 14, which are held in place by means of the set-screws 19. The under side of the work table 17 is also provided with a downwardly projecting boss or lug 20, provided with a horizontally arranged cylindrical opening adapted to receive one end of a rod 21, as shown. The rod 21 is adjustably mounted in the lug 20 by means of the set-screw 22. The other end of the rod 21 is squared and enlarged, as indicated by 23, and such enlargement is provided with a vertically arranged cylindrical hole adapted to receive a rod 24, which is adjustably mounted within by means of the set-screw 25. The rod 24 is bent at right angles, at 26, to form a horizontal arm 27, which extends over the work table 17. The end of this arm 27 is forked, as indicated by 28. The arm 27 is bent slightly in a horizontal

plane, so that the forked-end will lie substantially above the center of the work table 17.

Adjustably mounted, by means of the set-screws 50, on the posts 14, is a bridging member 51. The center of this bridging member is provided with a horizontally arranged bearing 52. Slidably mounted on the rods 14 is an H-shaped cross-head 55, as shown in Fig. 2, the ends of the vertical parts of this cross-head being provided with holes adapted to receive the rods 14, as shown. This cross-head 55 is provided with a horizontally arranged groove or slide 56. Attached to the upper end of one of the vertical ends of the cross-head 55 is a boss or lug 60, provided with a horizontally arranged circular hole adapted to receive the lower arm 67 of a U-shaped saw frame, which supports, between its ends, a scroll saw blade 68, in the usual manner. The arm 67 is adjustably mounted in the lug 60 by means of a set-screw 69.

Means are provided for reciprocating the cross-head 55 upwardly and downwardly on the posts or guides 14. Such means comprise a shaft 70 rotatably mounted in the bearing 52 and provided at its outer end with a crank 71 and operating handle 72. The inner end of the shaft 70 is provided with another crank 73, on the end of which is a short pin 74 having its end provided with a roller 75, operating in the groove 56 in the cross-head. The end of the pin 74 is slightly enlarged as indicated by 78, in order to retain the roller 75 in place.

It is obvious that rotation of the shaft 70, by means of the crank 71, will cause upward and downward reciprocation of the cross-head 55. The arm 67 of the saw-supporting frame is mounted in the part 60, so that the saw 68 will pass through a hole provided in the center of the work table 17. It will be seen that upward and downward movement of the cross-head 55 will cause upward and downward movement of the saw blade 68 through the hole in the work table, to operate on any material placed on the table in the usual manner. The arm 27 is arranged so that the saw blade 68 passes through the bifurcated end 28. This arm 27 serves to assist in holding the work down on the table 17. The vertical rod 24 may be adjusted upwardly or downwardly by

means of the set-screw 25, to adapt the height of the arm 27 to any desired thickness of work.

It will be noted that the posts or guides 5 14 are somewhat longer than necessary to accommodate the full length of travel of the cross-head 55. It will be noted also that the blade 68 is somewhat longer than such length of travel. Because of this construction, it is possible to move the bridging member 51 upwardly or downwardly on the posts 14, by means of the set-screws 50, in order to bring different parts of the blade 68 in operative relation with the table 17. 15 By this construction it is possible to distribute the wear on the blade 68 through substantially the entire length of the blade. This feature is especially useful in a case where one or more teeth of the blade 68 become broken or mutilated. When this happens it is not necessary to renew the blade, but by means of the set-screws 50, the bridging member 51 may be raised or lowered, thus changing the span of travel of the 20 cross-head, and accordingly changing the position of the blade 68 with respect to the table 17.

Although I have shown a scroll saw adapted to be operated by hand it is obvious, however, that without detracting from the spirit of this invention, the saw could be operated by power if desired; and while

I have shown and described certain embodiments of my invention, it is to be understood that it is capable of many modifications. Changes therefore in the construction and arrangement may be made without departing from the spirit and scope of the invention as disclosed in the appended claim, in which it is my intention to claim 35 all novelty inherent in my invention as broadly as possible in view of the prior art. 40

What I claim as new and desire to secure by Letters Patent, is:

A scroll saw comprising a base plate, two 45 vertically arranged parallel posts supported by the base plate, a work-supporting table mounted on the upper ends of said posts, a cross-head slidably mounted on said posts and carrying a saw frame, a saw blade 50 mounted in the saw frame and extending through a hole in the work-supporting table, and means for reciprocating the cross-head on said posts, said means comprising a bridging member adjustably mounted on 55 said posts and provided with a bearing having rotatably mounted therein a shaft carrying at one end an operating crank and at the other end a crank cooperating with a groove in the cross-head. 60

Witness my hand and seal this 25th day of November, 1921.

CARL A. MOBERG. [L. s.]
